(57) **CLAIM**

The ornamental design for an anchor device for a luggage support strap, as shown and described.

DESCRIPTION

FIG. 1 is an isometric view of the anchor device for luggage support strap embodying my new design.

FIG. 2 is front elevational view thereof.

FIG. 3 is a rear elevational view thereof.

FIG. 4 is a left side elevational view thereof, the right side elevational view being a mirror image thereof.

FIG. 5 is a bottom plan view thereof.

FIG. 6 is a top plan view thereof.

FIG. 7 is an isometric view of the anchor device, showing the lower plate separated therefrom.

FIG. 8 illustrates the anchor device attached to a luggage support strap of a piece of luggage, the luggage and the luggage support strap are shown in broken lines for illustrative purposes only and form no part of the claimed design.
